JOHANNES MICHAEL SCHMIERER, OF BERLIN-LICHTERFELDE, GERMANY

GAS DISCHARGE RELAY

Application filed November 6, 1930, Serial No. 493,824, and in Germany November 7, 1929.

My invention relates to electric relays or devices by means of which a relatively small amount of electrical energy may be made to control large quantities of power and more particularly to relays of the electric discharge type.

The well-known vacuum tubes, such as used in radio for the purpose of producing oscillations, amplification, or rectification, are relays in which small changes in grid potential produce comparatively greater changes in plate current. These tubes, which operate with a pure electronic discharge, have, however, the drawback that they require two different sources of operating currents; that is, a source of potential for supplying the electron discharge current through the tube and a further source of current for heating the cathode electrode and maintaining it at a high electron emitting temperature.

In view of this drawback, it has been proposed to use glow or gas discharge tubes, in place of pure electronic vacuum tubes; that is, tubes which contain a gas of definite composition and pressure and which do not require a heated cathode. Such gas tubes, however, have not gone into commercial use to any practical extent, on account of a number of drawbacks, such as rapid and early disintegration of the cathode material by ionic bombardment and the deleterious action of occluded gases in the cathode material, which make the tube operation both unstable and unreliable.

It is, accordingly, an object of my invention to provide a novel gas discharge tube of the type referred to, which is devoid of the above mentioned drawbacks and which operates on a single supply voltage and, thus, has numerous advantages over the customary electron vacuum tubes.

A more specific object of my invention is to provide a novel gas discharge tube, which exhibits increased stability of operation and which allows an easy and effective control of the discharge current, in accordance with small input currents or potentials.

These and further objects of my invention will become apparent from the following detailed description, made with reference to the

accompanying drawings, in which I have illustrated some embodiments of my invention. I wish it to be understood, however, that the description and the drawings are intended to be illustrative only of the broad inventive principle which may be embodied, as will become obvious in many modifications coming within its broad and most comprehensive scope, as expressed in the appended claims.

In the drawings:

Figure 1 illustrates a curve explanatory of the theoretical operation of a gas discharge tube relay, constructed in accordance with my invention.

Figure 2 is a simple electrical circuit from which the data for the curve shown in Figure 1 has been plotted.

Figures 3 and 4 show circuits, in accordance with my invention, in which my novel gas discharge tube may be used as an amplifier.

Figure 5 shows another modification of the circuits shown in Figures 3 and 4.

Figure 6 is similar to Figure 3, having an asymmetrically arranged control electrode in respect to the main discharge electrodes.

Figures 7 and 8 illustrate novel multiple discharge tubes, according to my invention, in which two electrode systems have been combined for the purpose of cascade amplification in a single tube.

Figure 9 shows a cross-section of a tube, embodied in my invention, by which the character of the operating characteristic may be varied, as desired.

Figure 10 shows a further way of changing the operating characteristic of a gas discharge tube, in accordance with my invention.

My invention is based upon a form of gas discharge which essentially differs from the well-known glow discharge occurring between a cathode and anode electrode disposed in a gaseous atmosphere. The discharge utilized in accordance with my invention occurs only at the very low intensities of operating current, as compared to the ordinary glow discharge, as known in the art. This discharge, as utilized in accordance with my invention, will hereinafter be termed "ante-glow" discharge, as it occurs prior to the glow dis-

charge proper when the voltage on the terminals of the discharge tube is gradually increased. In order to obtain such a form of discharge, I use a tube with two electrodes, which are placed sufficiently close to each other as to operate at a correspondingly low voltage, in such a manner that an independent discharge without the common negative glow is produced and maintained. With this kind of gas discharge, which I have called "ante-glow" discharge, there is a luminescent film adjacent to the anode electrode, the luminosity or brightness of which gradually decreases as it approaches the cathode electrode. A possible explanation of this phenomenon may be as follows: Due to the closeness of the two electrodes to each other and the low voltage operation, the electrons do not gain a sufficient velocity to ionize the gaseous molecules by collision, but the velocity is just sufficient to create the emission of light rays.

Figures 1 and 2 will explain these phenomena further.

Referring to Figure 2, I have shown a vessel v , such as a glass tube which is filled with a gas of proper nature and pressure, such as, for instance, with a mixture of three parts of neon and one part of helium, at a pressure of 10 millimeters Hg. Disposed within the vessel v are a cathode electrode c and an anode electrode a , both having the shape of a spirally wound wire, arranged juxtaposed to each other. The cathode and the anode electrodes are connected to a source of operating potential, such as battery B in series with a protective resistance w . By varying the voltage applied to the tube electrodes, such as by means of a potentiometer p and observing the variations in output current, a graphic showing of the operating characteristic, as schematically shown by Figure 1, may be plotted from the values thus obtained. This curve illustrates the discharge current i passing through the tube plotted as a function of the voltage e of the operating source B . From this curve it is seen that by increasing the voltage from zero to positive values, through the range x , the discharge current increases in substantially a direct proportion, according to a sloping curved or almost straight line. This gradual increase corresponds to the ante-glow operating range (x according to Figure 1). I have discovered that, in order to obtain a sufficiently broad range of ante-glow of the tube for utilization, such as for use of the tube as an amplifier or the like, the distance of the electrodes when utilizing gases of the nature mentioned hereinbefore, should not be greater than about 5 millimeters, or, in general, approximately not more than 10 times the amount of the "mean free path" of the particular gas used. A possible explanation of this ante-glow, as already pointed out, consists in the predomi-

nance of electrons over the ions during this condition, whereas, during the actual glow discharge, the number of ions will be considerably larger than the number of electrons present within the tube. This makes it obvious that, in order to obtain a condition having the properties of the ante-glow, the distance of the electrodes must be such that within the desired voltage range covering the pre-glow, the amount of ions produced remains substantially below the amount of the ionizing electrons. Then, if the voltages increase beyond the limiting point P of the ante-glow range, the number of ionizing electrons will have accumulated to such an extent that suddenly the ions will predominate over the electrons and, thus, bring about the normal glow discharge of the tube. As is well known, the "mean-free-path" is a constant for a given gas, being also dependent on the pressure of the gas and is the mean free distance through which one electron in such gas has to travel to assume sufficient velocity to produce ionization by collision with a gas molecule.

The density of the "ante-glow" current is considerably smaller than the density of the ordinary glow discharge current and, accordingly, the surface of the cathode has to be much larger than in an ordinary glow discharge tube carrying an equal load. Since, furthermore, in contra-distinction to the common glow discharge, the discharge is concentrated upon that part of the cathode surface from which the electrons are enabled to pass through the anode over the shortest distance, it is necessary to make the anode considerably larger than would be the case with an ordinary glow discharge tube. Otherwise, large portions of the cathode would remain unused.

It is, therefore, not sufficient that the distance between the cathode and anode be small at a single point only, but I have discovered that it is necessary to provide cathode and anode electrodes of such construction that a maximum number of points on the cathode and anode surface are equidistant; i. e., that a maximum of the anode surface is arranged parallel with the surface of a cathode, such as is the case with a cathode and anode structure as shown in Figure 2. If this condition and the proper spacing as above set forth is not fulfilled, the range of the ante-glow discharge will be restricted to y , Figure 1, corresponding to the operating curve in dotted lines, so that its utilization for practical purposes becomes prohibited.

The "ante-glow" discharge differs from the ordinary glow discharge further in that the starting voltage and the extinction voltage have the same value, while with the common glow discharge the starting voltage is considerably higher than the extinction voltage. Thus, if the terminal voltage of an

"ante-glow" discharge tube is increased as described, the "ante-glow" discharge is finally transformed into a glow discharge, as at point P of Figure 1. If the terminal voltage is then reduced, again the glow discharge does not extinguish at once at point P according to Figure 1, but only when it has dropped below its starting voltage. The starting voltage and extinction voltage within the "ante-glow" operating range of the tube, on the other hand, have exactly the same value corresponding to a very low current intensity, whereas, with the ordinary glow discharge, the starting voltage is considerably higher than the extinction voltage, the latter corresponding to a definite value of the current intensity.

I have discovered that no disintegration process takes place in "ante-glow" gas discharge tubes which have been operated during a period of 1,000 to 3,000 hours, nor could any essential change in the operating characteristic be observed, so that the main drawbacks of glow discharge or gas discharge have been overcome. This may probably be explained by the absence of any considerable ionized gas which ordinarily bombards the cathode.

In accordance with the present invention, I provide means for controlling the ante-glow discharge current primarily in the form of a further electrode, such as a grid electrode similar to the common electronic vacuum tubes. As is well known, in ordinary gas discharge or glow discharge tubes, in which the discharge is composed primarily or exclusively of electric ions, great difficulties are experienced in controlling the discharge current, such as by means of a grid electrode. In fact, such tubes have, up to the present, been used merely for producing a kind of trigger action, which is equivalent to a switching operation. It has not been possible heretofore to construct gas discharge tubes in such a manner as to enable a gradual and faithful control of the discharge current, in accordance with the variations of the input energy.

When, however, a tube is operated in accordance with the present invention, operating within the range of "ante-glow" as described, I have discovered that such tubes may be as easily and effectively controlled as is the case with the ordinary high vacuum electron tubes, as used for radio and other purposes. This may be explained by the presence of electrons, rather than ions, of which the "ante-glow" current is primarily or entirely composed, as pointed out above, whereby as effective and easy a control is possible as with pure electron tubes. This entails the possibility of various constructions and modifications of "ante-glow" control tubes, a few of which I have illustrated in the drawings Figures 3 to 10.

Returning to Fig. 2, I have shown a grid electrode g in the form of a solid member or cylinder, arranged outside the anode and cathode electrode.

Referring to Figure 3, this illustrates an "ante-glow" tube with two flat electrodes a , c and a control grid g arranged between such electrodes. The input energy shown at I , as, for instance, weak telegraphic signals, voice currents, or the like, is applied to the grid and cathode of the tube and a suitable biasing battery, which may be positive or negative, may also be provided, if found necessary. The current variations thus applied to the grid will occur in an amplified form in the output circuit of the tube and may be utilized in a desired manner, such as, for instance, by means of a telephone or loud speaker t .

Referring to Figure 4, this is a similar arrangement to Figure 3, the only difference residing in the connection of the input circuit carrying input or control currents between the anode and grid electrode, in place of to the grid and cathode.

In Figure 5 I have shown an alternative arrangement in which the discharge tube is provided with two grids g_1 and g_2 , to which the input circuit is connected.

According to Figure 6, which is essentially identical to Figure 3, the grid electrode g is arranged assymetrically between the cathode and anode, in place of a symmetrical arrangement, as according to Figures 3 to 5. By arranging the grid electrode in this manner in respect to the anode and cathode, it is

possible to modify the operating characteristic of the tube for using the tube for definite purposes, such as either for amplification or rectification, or also as an oscillator. It is, furthermore, possible to combine two or more electrode systems within a single vessel, such as shown by the multiple tube circuits of Figures 7 and 8. According to Figure 7, I have shown a tube with two electrode systems; that is, a common cathode and two individual anodes a_1 and a_2 and a grid electrode g . A coupling resistance W_c is arranged between cathode and anode a_1 , which serves to provide a sufficient coupling potential produced by the discharge current between cathode c and the first anode a_1 , whereby a second amplification in the anode circuit of the anode a_2 is obtained, which latter includes the translating device t . C_g is a blocking condenser for blocking the potential of the operating battery B against the grid electrode.

Figure 8 is a similar circuit to Figure 7, the only difference being that cathode and anode electrodes have been exchanged. Two cathode electrodes C_1 , C_2 cooperate with anode a . When a voltage is impressed across grid g and cathode C_2 , current flows over anode a and coupling resistance W_c to cathode

- C₂. The drop across resistance W_c controls the current flow to the receiver t .
- As a gas filling I preferably use a mixture of neon and helium with or without an addition of rare gases, at a pressure of from three to thirty-five millimeters Hg. The electrodes may consist of tantalum, tungsten, molybdenum, nickel, iron, cobalt, aluminum, or magnesium, that may be provided in a known manner with a coating of electro-positive metal or compound of such metals, in order to decrease the cathode drop of the tube and make it possible to use lower operating voltages.
- In order to secure a uniform or constant small electrode distance, the electrodes may, in general, be constructed with the surfaces arranged parallel and opposite each other. If, however, for obtaining a different operating characteristic in respect to both directions of the current flow, it is desirable to make the surface of one electrode considerably larger than the other electrode, this can, for instance, be obtained by using a solid cathode of large surface and an anode consisting of a wire net and, accordingly, presenting a smaller surface and arranged parallel to the cathode, such as shown in Figure 9. The same effect may be obtained by using concentric anode and cathode electrodes of different diameter, as illustrated in Figure 10.
- I wish it to be understood that I do not desire to be limited to the exact detail of construction as shown and described, for obvious modifications will occur to a person skilled in the art.
- What I claim is:
1. In a system for relaying weak electric currents, an ionic tube, including a pair of cold electrodes close together, means for impressing a voltage across said electrodes, of a value such as to maintain the tube in a state of ante-glow discharge and control means for introducing current variations in said discharge current, whereby said discharge current is an amplification of variable control currents applied to said control means.
  2. An ionic tube, including a pair of cold electrodes close together, means for impressing a voltage across said electrodes of a value such as to maintain said tube in a state of ante-glow discharge and a control electrode arranged to influence said discharge.
  3. An ionic tube, including a pair of cold electrodes close together, means for impressing a voltage across said electrodes, of a value such as to maintain said tube in a state of ante-glow discharge and a grid electrode arranged between said cold electrodes.
  4. An ionic tube, including a pair of cold electrodes, means for impressing a voltage across said electrodes, said voltage and the spacing of said electrodes being of such value as to maintain the tube in a state of ante-glow discharge and a control electrode for influencing said discharge.
  5. An ionic tube, including a pair of cold electrodes close together, means for impressing electric voltage across said electrodes, said voltage and the spacing of said electrodes being such as to maintain said tube in a state of ante-glow discharge and a grid electrode arranged between said electrodes for influencing said discharge.
  6. An ionic tube, including a pair of cold electrodes, arranged close together and parallel to each other, means to impress an electric voltage across said electrodes, said voltage and the spacing of said electrodes being of a value such as to maintain said tube in a state of ante-glow discharge and a control electrode for influencing said discharge.
  7. An ionic discharge tube, including a pair of cold electrodes arranged parallel to each other at a distance less than ten times the mean free path of the gas included in said tube, means for impressing an electric voltage across said electrodes of a value such as to maintain said tube in a state of ante-glow discharge, and a grid electrode arranged between said electrodes for controlling said discharge.
  8. In an electrically controlled system, a control circuit, a circuit arranged to be controlled by said control circuit, means interposed between said circuits comprising a gas discharge tube having a pair of cold electrodes, series means to said circuit to be controlled impressing a predetermined voltage across said electrodes of such value as to maintain the discharge of said tube in a state of ante-glow, and a control electrode connected to said control circuit for influencing said discharge.
  9. In an electrical control system comprising a control circuit, a circuit arranged to be controlled by said control circuit, means interposed between said circuits comprising a gas discharge tube having a pair of cold electrodes, series means to said circuit to be controlled for impressing a predetermined voltage across said electrodes of such value as to maintain said tube in a state of ante-glow discharge, and a grid electrode between said cold electrodes connected to said control circuit for influencing said discharge.
  10. In an electrical circuit arrangement, a gas discharge tube including a pair of cold electrodes, a circuit for impressing a predetermined voltage lower than the glow discharge ignition voltage across said electrodes, a control electrode for influencing said discharge and a control circuit connected to said control electrode for producing corresponding variations of the discharge current of said tube.
  11. In an electrical circuit arrangement, a gas discharge tube including a pair of cold electrodes arranged parallel to each other, a

circuit for impressing a predetermined voltage lower than the glow discharge ignition voltage, a grid electrode arranged between said cold electrodes, a control circuit connected to said grid electrode for influencing said discharge for producing corresponding variations in said first circuit.

12. In an electrical circuit arrangement, a gas discharge tube including a pair of cold electrodes, a circuit for impressing a predetermined voltage lower than the glow discharge ignition voltage across said electrodes, a grid electrode arranged intermediate said cold electrodes, a control circuit connected to said grid electrode and one of said cold electrodes for influencing said discharge and producing corresponding variations in said first circuit.

13. In an electrical circuit arrangement, a gas discharge tube including a pair of cold electrodes, arranged parallel to each other and at a distance less than ten times the mean free path of the gas included by said tube, a circuit for impressing a predetermined voltage lower than the glow discharge ignition voltage across said electrodes, a grid electrode arranged between said cold electrodes and a control circuit connected to said grid electrode and one of said cold electrodes for influencing said discharge and producing corresponding current variations in said first circuit.

14. In an electrical circuit arrangement, a gas discharge tube including a pair of cold electrodes, of different surface and arranged parallel to each other, a circuit for impressing a predetermined voltage lower than the glow discharge ignition voltage across said electrodes, a grid electrode arranged between said cold electrodes and a control circuit connected to said grid electrode and one of said cold electrodes for influencing said discharge and producing corresponding variations in said first circuit.

15. In an electrical circuit arrangement, a gas discharge tube containing three parts of neon and one part of helium at ten millimeters pressure Hg., a pair of cold electrodes within said tube arranged parallel to each other and at a distance less than five millimeters, a circuit for impressing a predetermined voltage lower than the glow discharge ignition voltage across said electrodes, a grid electrode arranged between said cold electrodes and a control circuit connected to said grid electrode and one of said cold electrodes for influencing said discharge for producing corresponding current variations in said first circuit.

16. In an ionic tube having gas at a predetermined pressure, a pair of electrodes, the distance from every point of one of said electrodes to the other electrode being uniform, means for applying a predetermined voltage

between said electrodes, the gas pressure, spacing of electrodes and voltage maintaining the tube in an ante-glow.

In testimony whereof I affix my signature.
